UNITED STATES PATENT OFFICE.

EDWARD WRIGHT, OF WORCESTER, ASSIGNOR TO THE DAVIS & FURBER
MACHINE COMPANY, OF NORTH ANDOVER, MASSACHUSETTS.

SHEDDING AND SHUTTLE-BOX-OPERATING MECHANISM FOR LOOMS.

SPECIFICATION forming part of Letters Patent No. 425,843, dated April 15, 1890.

Application filed September 26, 1889. Serial No. 325,187. (No model.)

To all whom it may concern:

Be it known that I, EDWARD WRIGHT, a citizen of the United States, residing at Worcester, in the county of Worcester and State of Massachusetts, have invented certain new and useful Improvements in Shedding and Shuttle-Box-Operating Mechanism for Looms, of which the following, together with the accompanying drawings, is a specification sufficiently full, clear, and exact to enable persons skilled in the art to which this invention appertains to make and use the same.

The prime object of my present invention is to provide a shedding mechanism and shuttle-box-operating mechanism for looms which shall be simple in construction, efficient and durable in operation, convenient for attendance, and in which the members 20 can be readily taken apart and reassembled.

Another object is to provide for the purposes of operating the shuttle-boxes and harnesses of looms a combination of mechanism, wherein the vibrator-gears from which the 25 jacks are actuated are operated by a single continuously-rotating cylinder-gear.

These objects I attain by mechanism constructed and organized for operation substantially as explained in the following detailed 30 description, the particular subject-matter claimed as new and of my invention, and to be herein embraced by Letters Patent, being hereinafter definitely specified.

In the drawings, Figure 1 is a plan view of 35 such parts of a loom as will illustrate the nature of my invention. Fig. 1^a shows the jaw of the clutch for driving the shedding mechanism. Fig. 2 is a rear elevation of one end of a loom embracing my improved mechanism. Fig. 3 is a view on a somewhat larger scale, showing the levers and pulleys for actuating the shuttle-box-operating chains. Fig. 4 is a sectional view looking from the front, showing the arrangement of the actuating 40 mechanism, jacks, and connections, the vibrating arms being shown as depressed. Fig. 5 is a front view of the gearing whereby motion is transmitted to the pattern-chain from the cylinder-shaft. Fig. 6 is a sectional view 45 showing the manner of joining the connecting

bars and jacks. Fig. 7 is a transverse vertical section showing the fulcrum-support, the vibrator-bars, and the guard for retaining said bars in connection therewith. Fig. 8 is a vertical sectional view looking from the rear, 55 showing the arrangement of the operating mechanism and shuttle-box connections, the vibrator-bars being shown as elevated and the crank-gears in mesh as when effecting movement. Fig. 9 is a detail view of the unlocking bar or retractor and its arms. Figs. 10 and 11 show the form of the cams for operating the unlocking-bar.

In referring to parts, A denotes the frame of suitable construction to support the operating devices.

B indicates the jacks for operating the harness-frames B', which jacks and harnesses can be constructed and arranged for operation in any suitable or well-known manner, 70 and b indicates the jacks for the shuttle-boxes. Upon the upper part of the projecting head-frame, at the end of the loom, there is arranged a revoluble cylinder C, the shaft or axis C' of which is supported in bearings 75 at the front and rear ends thereof, as at a a. Said cylinder is provided upon a part of its periphery with gear-teeth that extend from end to end of the same, a sufficient number of teeth being formed thereon to effect a one-half revolution of the vibrator or crank gears, the other portion of its periphery being plain or without teeth.

Beneath the cylinder-gear C there is arranged a series of vibrator-bars D, the number of such bars corresponding with the number of harness and shuttle-box actuating jacks, a greater or less number being employed according to the requirements of the loom or work. Said vibrator-bars are fulcrumed on a support or rod D', that extends across the frame from front to rear, near the central part of the head, while the outer ends of said vibrator-bars are arranged to move up and down in guideways on a transverse plate 85 A², attached to the outer end of the head-frame. Adjacent to the ends of the vibrator-bars and supported on the plate A² there is a rod A³, upon which a series of springs d³ are arranged for respectively pressing down the 90 95 100

several vibrator-bars. Beneath the ends of the vibrator-bars there is a stop A⁴, which prevents said bars from dropping too low.

The inner ends of the vibrator-bars D are made to hook over the fulcrum-rod D', and a bar H is pivoted to the frame at h just above the fulcrum, which bar hangs downward and serves as a guard over the hooked ends to prevent the vibrator-bars lifting or being forced upward at their fulcrum. Said guard-bar H can be swung upward for releasing the vibrator-bars when it is desired to remove one or more of them from position. The guard H may be a bar extending completely across the frame, or a rod having thereon a series of loose sections that swing down over the end of the vibrator-bars. Upon each of the vibrator-bars there is a revoluble gear F, mounted on a stud d, that projects from the side of the bar. Said gear is provided with a crank or wrist pin e, from which a connecting-rod E extends to the jack B or b, the jack being moved back and forth by the revolution of the crank-gear F. Beneath the series of vibrating bars there is arranged the cylinder or sprocket J, which carries the pattern-chain K, the lower projecting portion of the vibrator-bars resting thereupon, and by means of the balls or indicators upon the bars of said chain the vibrator-bars D are elevated or thrown upward for engaging the crank-gears F with the cylinder-gear C.

Pivoted to the side of the vibrator-bar is a dog or locking-detent I, that engages the teeth of the gear F when depressed. A spring i is arranged on the bar, as indicated, whereby said dog is normally pressed into engagement with the gear. Above the row of dogs I and mounted in bearings a⁵ on the frame is an oscillating retractor or unlocking-bar L, the lower part of which is fitted with a groove l along its under side. This retractor or unlocking-bar is oscillated by means of cams m and m', mounted on the cylinder-gear shaft C' at the respective ends of the cylinder-gear; or, if preferred, both cams can be at one end, said cams engaging with upwardly and downwardly curved arms M and M', fixed to the retractor-axle. The retractor is best provided with a backwardly-extended arm L², that engages with leather-padded stops n n, fixed on the frame, which stops prevent the arms coming in contact with the flat part of the cams and hammering thereon, thus preventing much noise.

The dogs I are severally provided with an upwardly-extended lug or projecting top, which is adapted to enter the groove l of the retractor or unlocking-bar L when the latter is swung forward, at which position the tops of the locking-dogs and the groove are in conjunction. When a vibrator-bar is elevated, the top of the dog arranged thereon enters the groove l in the locking-bar, and said bar by its backward movement overcomes the pressure of the spring i and forces the nose of the dog out from the teeth of the crank-

gear F, thereby releasing said gear just at the instant its teeth are going into mesh with the teeth on the cylinder-gear C. The cylinder-gear is preferably made in sections, the part which actuates the harness mechanism and that which actuates the shuttle-box mechanism being separately fixed on the shaft C', so that one section may be adjusted to act slightly in advance of the other. Said cylinder can, however, be made integral or of one piece if in any instance so desired.

Power and motion are imparted to the cylinder-gear C through beveled gears G' by a shaft G, which is in turn rotated by a suitable train of gearing G² from the main or crank shaft of the loom. This gearing and shaft are arranged as shown in Figs. 1 and 2, or in other suitable manner for imparting a continuous forward rotary movement to the cylinder-gear C. A clutch N is arranged on the shaft G for throwing the shedding mechanism into and out of action. Said clutch is operated by a fork and rocker-shaft N', arranged in bearings on the frame and provided with a handle N² near the front of the loom. The jaws of the clutch N are made as in Fig. 1^a, or of such suitable form that they can be thrown into mesh only at one particular point in their revolution, so that the main crank-shaft O and lay O² of the loom and the cylinder-gear C that controls the harness and shuttle-box mechanism will operate in unison and cannot be deranged in their relation of action by the shifting of the clutch when stopping and starting the shedding mechanism.

The connecting-bars E are at one end pivoted to the wrist-pins e of the crank-gears F, and are curved downward beneath the fulcrum-bar D', and their rear ends are each provided with a dovetailed stud t, (see Fig. 6,) which lock into a correspondingly-shaped recess formed in the jack, and thus makes a pivot-connection therewith.

The jacks B are preferably so constructed that the dovetailed studs can be lifted from the recesses for disconnecting the parts at any time, so that the connecting-links E can readily be detached, the vibrator-bars taken out and replaced, or the jacks removed from the loom in a ready and convenient manner. The jacks are fulcrumed to swing on an axis or bar B⁴, supported on the side of the frame in ordinary manner. Any desired number of sets of vibrator-bars D, crank-gears F, and connections E may be employed in the series, according to the number of harnesses required in a loom, all being of the same general construction and all actuated from the single cylinder-gear C. For working the shuttle-box mechanism, instead of the connecting-bar being attached to a long jack, it is attached to a short dependent jack or lever b, which is pivoted at its upper end a³ to a support or overhanging part of the frame. From two of the jacks b chains P extend to the respective shuttle-boxes S at the opposite ends of the loom, said chains pass-

ing over suitable guide-sheaves, as required. Adjacent to the first and third, actuating-jacks *b*, to which the chains *P* are connected, are arranged two pulleys *R* and *R'*, that carry said shuttle-box chains, and the alternate jacks or actuating-levers adjacent to those to which the chains are attached have connected therewith a pulley *T*, that swings between the pulleys *R* *R'* and serves as a take-up on the chain. (See Figs. 2, 3, and 8.) When the jack *b* is swung forward, the take-up pulley draws a portion of the chain between the pulleys or guides *R* *R'* and thus lifts the shuttle-boxes, and when said take-up pulley *T* is swung back the chain is allowed to straighten, which allows the shuttle-boxes to drop.

The shuttle-boxes can be constructed and arranged in well-known manner, and the chains *P* connected therewith for shifting the same as heretofore employed or substantially as indicated in Fig. 2.

The pulley *R'* is mounted on an adjustable or swing bracket *R*², suitably attached to the frame and provided with set-screws *r*, whereby it can be adjusted up or down to take up or slacken the chain *P*, and thereby regulate the position of the shuttle-box in relation to the race-plate to bring the boxes accurately on a level therewith.

The pattern-chain may be of well-known form and supported in the usual manner. Said chain is operated by means of a crank *V*, fixed on the cylinder-gear shaft *C'*, which crank actuates a star-wheel *W*, supported on an intermediately-disposed stud, which also carries a gear *W'*, that is attached to the star-wheel and meshes with a corresponding gear *J'*, fixed on the chain-cylinder arbor. (See Fig. 5.) The chain is moved with a step-and-step movement as the crank *V* engages with and leaves the star-wheel. A hand-crank *x* is arranged on the front end of the cylinder-gear shaft for turning the mechanism when "finding the picks." For this purpose it is simply necessary to throw out the clutch *N* and revolve the crank *x* either backward or forward until the chain and mechanism are brought to the position desired.

The guide-plate *A*², which confines the ends of the vibrator-bars, is best hinged or detachably connected to the frame at its ends, so that it can be displaced or swung downward away from the ends of the vibrator-bars, carrying with it the springs *d*³, thus affording ample facility for the removal of the bars *D* or any one of them without disturbing others. The guide-plate can be secured to the frame when in normal position by a latch, dog, pins, or bolts suitably arranged to connect it with the frame, and to be conveniently removed when desired.

In the operation the cylinder-gear *C* is rotated continuously in the direction indicated by the arrow by a regular motion corresponding with the movement of the main shaft *O*. The action of the balls of the pattern-chain

successively throws up the respective vibrator-bars, bringing their crank-gears into position where their teeth will engage with the teeth of the cylinder-gear as the latter revolves. At this upward movement of the vibrator-bar the lug on the head of the locking-dog enters the slot in the retractor or unlocking-bar, and said bar, being at the proper instant thrown back by the action of the cams and the follower-arm, lifts the detent from between the teeth of all the series of crank-gears which are elevated at the instant when the latter are brought into mesh with the cylinder-gear, and said crank-gears are then moved a one-half revolution by the toothed portion of the cylinder-gear, at which position they are stopped and locked by reason of the unlocking-bar moving forward under control of the cams and causing or allowing the dog to drop between the teeth of the gear. In case the vibrator-bar *D* is held in elevated position, the crank-gear is again unlocked by the swinging back of the unlocking-bar and a continued forward rotative action is imparted to the crank-gear to the extent of another half-revolution as the teeth of the cylinder-gear come around. All of the locking detents or dogs in the series on vibrator-bars which are raised by the pattern-chain are thrown out of engagement with their crank-gears, while the dogs on the vibrator-bars which are not raised remain in clutch with their gears, as they are not within the range of action of the retractor or brought into contact with the unlocking-bar *L*. The rotation of the crank-gears *F* imparts reciprocative action to the connecting-bars *E*, which motion is transmitted to the jacks *B* and levers *b*, to which the respective connecting-bars are attached, and from thence to the harnesses and shuttle-boxes in their required order of action.

In the operation of the shuttle-box action, when all of the jacks *b* are all swung back or at outward position, the chain *P* is nearly straight and the shuttle-boxes *S* are at their lowest position with the first or top box in line with the race. Then when the jack *b*, to which the chain *P* is attached, is thrown inward, the rod *P*³ is elevated one step by the draft on the chain and the second box is brought to position. When the jack to which the chain is attached is swung back, and the jack having the arm and carrying the take-up pulley *T* is drawn outward, the box-rod is elevated two steps and the third shuttle-box is brought to position. When both jacks, the one to which the chain is attached and the one to carrying the take-up pulley, are drawn outward, the box-rod *P*³ is raised three steps and the fourth or bottom box is brought into position level with the race. Thus any box in the series can be brought to position as required.

It will be understood that I do not claim, broadly, the operation of shuttle-boxes of looms by a chain from a shedding mechanism,

as my invention relates to the peculiar means, substantially as described, for effecting such operation.

It will be noticed that the action of the 5 crank-gear F is an intermittent continued rotation in forward direction, and by reason of this continued forward movement the teeth of the gears, the crank-pins, and arbors wear more uniformly and do not become shaky. 10 The mechanism is thus rendered more durable, while at the same time the parts work with a much easier action.

In my improved mechanism I employ but 15 a single cylinder-gear, which is revolved constantly in one direction. The rotation of crank-gears in the shedding mechanism and shuttle-box-operating mechanism of looms by a single revolving cylinder-gear and by a forward movement only is an important feature 20 of my invention, and is broadly included as within the scope of my claims, howsoever the connections, vibrators, and jacks may be arranged for transmitting the motion to the harnesses and boxes.

25 The advantages incident to this invention are the simplicity of construction, fewness of parts, and the ease and facility with which the parts can be separated and reassembled.

What I claim as of my invention, to be here- 30 in secured by Letters Patent, is—

1. In a loom, a series of vibrator bars or levers having mounted thereon crank-gears that act with a forward intermittent rotation, connecting-bars from the crank-gear cranks to the 35 jacks, a single constantly-rotating partially-toothed cylinder-gear whereby said crank-gears are rotated, a series of locking-dogs individually engaging with the respective crank-gears, and a retractor that releases the individual lock of a crank-gear when elevated into 40 mesh with said cylinder-gear, in combination with a movable pattern surface or chain having indicators that lift said vibrator-bars, and a system of jacks to which the harnesses and 45 shuttle-boxes are connected, substantially as set forth.

2. In combination with the cylinder-gear, the vibrator-bar, the crank-gear, the jack-connecting bar having a jack connected therewith, the locking detent or dog supported on 50 the vibrator-bar and engaging a recess in the crank-gear for holding said gear from rotating when out of mesh, a spring for pressing forward said dog, and means for retracting said locking-dog, substantially as set forth.

3. The combination, with the cylinder-gear, the swinging jacks and their connecting-bars, the series of crank-gears, and the vibrator-bars on which said crank-gears are supported, of a 55 series of locking dogs or detents that normally engage, respectively, with said crank-gears to prevent rotation thereof, and a retractor disposed in normal disengagement with the series of locking-dogs, but at position

for engaging and throwing said locking-dogs 65 from the crank-gears when the latter are thrown up for engagement with the cylinder-gear by the elevation of the vibrator-bars, and the pattern surface or chain having indicators thereon, whereby said vibrator bars are 70 lifted, substantially as set forth.

4. The retractor or unlockng bar provided with an arm or guard, and stops n for limiting the movement thereof to prevent ham- 75 mering of the follower-arms upon the cams, in combination with the cylinder-gear, retractor-actuating cams, vibrator-bars, crank-gears, locking-detents, the jacks, and jack-connecting bars, as set forth.

5. The combination of the cylinder-gear, 80 the vibrator-bars, the vibrator-gears, the spring-pressed locking-dogs that engage said gears, and a retractor or throw-off device operated synchronously with the rotation of the cylinder-gear and having a grooved bar that 85 engages the tops of the locking-dogs when elevated and unlocks the crank-gears as they approach the cylinder-gear, the connecting-bars, and jacks, all substantially as described.

6. In combination, substantially as speci- 90 fied, the pair of swing jacks or levers b, two guide-pulleys having their axes at stationary position on the frame, the take-up pulley carried by or connected to one of said swing-jacks arranged to swing into the space be- 95 tween the two guide-pulleys, the shuttle-box-lifting chain having its end attached to the other of said swing-jacks, the vibrator-bars, the operating cylinder-gear, the crank-gears, connecting-bars joining said swing-jacks with the crank-gears, the gear-locking dogs, the retractor, and the pattern-chain, all substan- 100 tially as described.

7. The pulley R' and adjustable support for the same, and screws for adjusting the 105 said support, in combination with the swing-jacks b, pulleys R, R', and T, and shuttle-box-lifting chain P, as set forth.

8. The series of springs, and the supporting rod or bar arranged across the frame and ex- 110 tends through the coils of said springs which project therefrom and press upon the free ends of the vibrator-bars, substantially as described, in combination with the vibrator-bars, crank-gears, cylinder-gear, jack-con- 115 nections, and pattern-chain, as set forth.

9. The displaceable guide-plate A², pivoted or detachably connected with the frame, in combination with the vibrator-bars having their movable ends in engagement with the 120 guideways of said bars, substantially as and for the purpose set forth.

Witness my hand this 21st day of September, A. D. 1889.

EDWARD WRIGHT.
